Patented Aug. 11, 1959

185,875

AUTOMOBILE TAIL LAMP

Homer C. Lagassey, Jr., Royal Oak, Mich., assignor to Chrysler Corporation, Highland Park, Mich., a corporation of Delaware

Application June 26, 1958, Serial No. 51,543

Term of patent 7 years

(Cl. D48—32)

Fig. 1 is a front elevational view of an automobile tail lamp showing my new design;

Fig. 2 is a side elevational view thereof; and

Fig. 3 is a reduced sectional view taken on the line 3-3 of Fig. 1.

I claim:

The ornamental design for an automobile tail lamp, substantially as shown.
